UNITED STATES PATENT OFFICE

146,591

DESIGN FOR A TEXTILE FABRIC

Julien Binford, Fine Creek Mills, Va.

Application January 23, 1947, Serial No. 136,329

Term of patent 3½ years

(Cl. D92—1)

To all whom it may concern:

Be it known that I, Julien Binford, a citizen of the United States of America, residing in Fine Creek Mills, county of Powhatan, and State of Virginia, have invented a new, original, and ornamental Design for a Textile Fabric, of which the following is a specification, reference being had to the accompanying drawing, forming part thereof, wherein, the figure is a plan view of a textile fabric showing my new design. The dot and dash lines on the drawing outline a design unit, which unit is repeated in regular succession as indicated by the extensions beyond the unit boundaries.

I claim:

The ornamental design for a textile fabric, substantially as shown and described.

JULIEN BINFORD,
